(57) CLAIM

I claim the ornamental design for the purse with beaded handles, substantially as shown and described.

DESCRIPTION

FIG. 1 is a perspective view of the purse with beaded handles in accordance with one aspect of the design.

FIG. 2 is a front view of the purse with beaded handles of FIG. 1, showing the design, the rear view being a mirror image thereof.

FIG. 3 is a top view of the purse with beaded handles shown in FIG. 1, showing the design.

FIG. 4 is a left-side view of the purse with beaded handles of FIG. 1, showing the design, the right-side view being a mirror image thereof; and,

FIG. 5 is a bottom view of purse with beaded handles of FIG. 1, showing the design.
